CLAIM

The ornamental design for a handle for a food box as shown and described.

DESCRIPTION

FIG. 1 is a first perspective view taken from a front, left side of a handle for a food box according to our design; FIG. 2 is a second perspective view thereof, shown in environmental use;

FIG. 3 is a front view thereof;

FIG. 4 is a rear view thereof;

FIG. 5 is a right side view thereof;

(Continued)

FIG. 6 is a left side view thereof;
 FIG. 7 is a top view thereof; and,
 FIG. 8 is a bottom view thereof.

The broken lines show portions of the handle for a food box and form no part of the claimed design. The food broken lines that show the box in FIG. 2 illustrate environment only and form no part of the claimed design.
